UNITED STATES PATENT OFFICE.

PAUL G. ZIMMERMANN, OF KEYPORT, NEW JERSEY, ASSIGNOR TO AEROMARINE PLANE & MOTOR COMPANY, OF NEW YORK, N. Y., A CORPORATION OF NEW YORK.

STABILIZER LOCK.

Application filed July 11, 1923, Serial No. 650,769. Renewed January 23, 1926.

The invention relates to airplanes; and it comprises a limit lock for a control surface, particularly for an adjustable stabilizer, so that, in event of failure of the adjustable device securing the stabilizer, the latter will become automatically locked against movement in either direction. 55

In the accompanying drawing illustrating the invention:

10 Fig. 1 is a side elevation of the horizontal and vertical stabilizer, with the covering on the vertical stabilizer broken away to show in full lines the adjusting and locking means for the horizontal stabilizer;

15 Fig. 2 is a fragmentary side elevation on a larger scale; and

Fig. 3 is a longitudinal section on the line 3—3 of Fig. 2, showing the position the parts assume when the horizontal stabilizer 20 is locked against movement in either direction.

The drawing shows the horizontal stabilizer 2, and the fixed fin, or vertical stabilizer, 3 of a flying-boat. The frame 4 of the fin constitutes a supporting frame beneath the horizontal stabilizer, which will be termed simply the stabilizer, and which in this instance is hinged at its trailing edge to the rear part of the fin, as indicated at 5.

30 A vertical rod 6 is guided in the frame of the fin and pinned at its upper end to the forward part of the stabilizer, and its lower portion 7 is screw-threaded and carries a nut 8 in the form of a drum. This drum is held in a recess 9 of the fixed frame against movement either up or down, and may be operated through a control band (not shown) to raise or lower the rod 6, so as slightly to vary the angle of the stabilizer 35 in order to trim the flying machine longitudinally.

A short lock rod 10, adjacent and parallel with the rod 6, is also pinned at its upper end to the stabilizer, and slides in bearings 45 11 and 12 on the fixed frame. Pinned to this rod between the bearings is a collar 13 carrying downwardly extending spring blades 14. These blades are tensioned to spring outwardly, but are normally confined 50 in the bearing 12 forming the lower part of the guide. The arrangement is such that the lock rod will slide up or down freely when the stabilizer is adjusted within the intended, limited range, but should the sta-

bilizer tend to swing upward in an extreme manner, as the result of breakage of the adjustable support or otherwise, the lock rod will become fixed and hold the stabilizer against further movement either up or down. 60

In the illustrated construction this results from the tips of the blades 14 springing slightly outward from the confinement of the bearing passage into a cup 15 at the top of the bearing 12, at or immediately before 65 the moment when the shoulder of the collar 13 abuts against the bottom of the upper bearing 11. The cup 15 confines the blades in their locking position, and by resting against the ledge at the bottom of the cup 70 they rigidly resist any downward movement of the rod and stabilizer. The latter is thus held fixedly in a safe position.

The foregoing constitutes a simple and preferred embodiment of the invention, but 75 I wish it to be understood that I do not limit myself to the precise construction as various forms of the limit lock which I regard as my invention may be devised.

What I claim as new is:

1. A lock for a movable control surface comprising a vertical lock rod connected to the surface, a support having a guide in which said rod can slide with the movement of the surface, the rod having a shoulder to 85 abut a portion of the support at the limit of permitted upward movement, and spring blade means on the rod adapted to snap out from confinement in the guide at such limit so as to prevent downward movement. 90

2. In an airplane having a movable stabilizer, a fixed frame, and adjustable securing means for the stabilizer, a lock rod connected to the stabilizer and guided in the fixed frame, and a spring catch arranged to act 95 when the lock rod is raised to a predetermined extent.

3. In an airplane, the combination with a movable stabilizer, a fixed fin beneath the stabilizer, and means adjustably securing 100 the stabilizer to the fin, of a limit lock between the stabilizer and the fin permitting intended movement of the stabilizer and operative at a predetermined elevation to cause the stabilizer to be thereafter held against 105 movement in either direction.

PAUL G. ZIMMERMANN.
